AIR VENT GUARD

Harvey K. Maxam, Francisco, Ind.

Application November 25, 1936, Serial No. 112,809

2 Claims. (Cl. 137—122)

This invention relates to a guard for the air vent devices primarily of steam heating systems.

At the present time, especially in schools and where there are children, such air vent devices, which are screwed in place, are turned mischievously from an upstanding position to various angles and in addition the vent openings are plugged with sticks, gum and the like, seriously interfering with the escape of air and heating 10 of the radiators to which the devices are attached.

It is a prime object of the present invention to provide a means which will prevent the said 15 tampering with or displacement of the air vent devices so that they will efficiently function at all times.

It is also aimed to provide a structure in the nature of an attachment which is exceedingly 20 simple, inexpensive and durable, and will further prevent the turning of the air vent devices on their screw threads, eventually resulting in the stripping and ruining thereof.

Various additional objects and advantages will 25 become apparent from a consideration of the description following taken in connection with accompanying drawing illustrating an operative embodiment.

In said drawing:—

Figure 1 is a view showing a fragment of a 30 steam heating radiator equipped with an air vent device, and also with my improvements;

Figure 2 is a view showing my improvements in plan in connection with a cross sectional part of the radiator;

Figure 3 is a vertical sectional view taken on the line 3—3 of Figure 1;

Figure 4 is a view similar to Figure 1 but of a modified form, and

Figure 5 is a view showing the modified form 40 in plan and in connection with a cross sectional part of the radiator.

Referring specifically to the drawing, and first to the form of Figures 1 to 3, a conventional radiator, as used in a steam heating system is fragmentarily shown at 10, having an air vent device 11 of conventional form, screw threaded thereto as at 12. These air vent devices, around children, as in school rooms, are frequently mischievously turned by the children at the screw threaded connection 12, displacing the device out of the upstanding position and unduly wearing the screw threads 12, which prevents efficient heating and causes undue wear on the screw threads 12.

In accordance with the present invention, a novel attachment is employed as at 13, preferably stamped from a single sheet or strip of metal.

This attachment comprises a band 14 which surrounds the device 11 and which at its free ends terminates in jaws 15, to embrace a leg of the radiator and which jaws at their free ends have hooks 16. In order to augment the inherent 5 ability of the jaws 15 to spring toward each other and to grip the leg of the radiator, a bolt is employed as at 17 which passes through suitable openings in the clamp between the device 11 and the leg of the radiator and which has a nut at 18, operable thereon to effect a binding action of the jaws on the radiator leg and of the band 14 on the device 11.

In addition, said attachment 13 employs a 15 guard finger 19 which extends upwardly from the band 14 and over and relatively close to the air outlet or vent opening at the top or apex of the device 11.

It will thus be seen that the device not only prevents turning the air vent device by hand, but it 20 also guards the vent opening against the placing of obstructing means in such opening.

As there are various types of radiators and air 25 vent devices marketed and in use, it is obvious that the invention may be varied in accordance therewith. For example, in Figures 4 and 5, the air vent device 11' is different in shape but similar in function to that at 11, being connected by a screw threaded nipple 12' to the radiator 10'. In the present instance, the attachment is designated 13' and is identical with that at 13 except the band 14', functioning like that at 14, is substantially square rather than round, to conform to the shape of the device 11'.

I claim as my invention:—

1. An air vent attachment of the class described comprising a band to embrace an air vent device, jaws extending from the band for attachment to a radiator, means extending from the band and integral therewith for disposition over and relatively close to the vent opening of said device consisting of a finger, to prevent foreign matter entering the vent opening in said air vent device, and means operable to simultaneously bind the jaws to the radiator and the 45 band to the device.

2. An air vent attachment of the class described comprising a band to embrace an air vent device, jaws extending from the band for attachment to a radiator, means extending from the band for disposition over and relatively close to the vent opening of said device consisting of a finger, means operable to bind the jaws to the radiator and the band to the device, comprising a bolt, hooks on the free ends of the jaws, and 50 said finger being integral with the band.

HARVEY K. MAXAM.
